(57) **CLAIM**

We claim the ornamental design for an interface for lower front panel for laundry appliance, as shown.

DESCRIPTION

FIG. 1 is a pictorial view of a interface for lower front panel for laundry appliance design of the present invention; FIG. 2 is a perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines are for illustrative purposes only and form no part of the claimed design.
